UNITED STATES PATENT OFFICE.

ISRAEL HESS, OF GOSHEN, INDIANA.

GRAIN-SEPARATOR.

SPECIFICATION forming part of Letters Patent No. 322,820, dated July 21, 1985.

Application filed April 10, 1885. (No model.)

To all whom it may concern:

Be it known that I, ISRAEL HESS, a citizen of the United States, residing at Goshen, in the county of Elkhart and State of Indiana, 5 have invented certain new and useful Improvements in Grain-Separators; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

15 My invention relates to grain-separators; and the novelty consists in the construction, arrangement, and adaptation of parts, as will be more fully hereinafter set forth, and specifically pointed out in the claims.

20 I provide a peculiar upper or chaff screen having cross-bars with abrupt sides in one direction and inclined sides in the other. The depending edges of the abrupt sides are scalloped to present numerous faces to the draft and to equalize the same, and this upper screen 25 inclines downwardly away from the fan.

I do away with the necessity of shoes, and have the screens occupy the entire width of the casing. Each screen is oscillated by connections, and flexible shedding-cleats are provided to prevent the grain from wedging between the screens and the sides of the casing. The several screens are given differential movements, and a carrier and elevator may 35 be provided to carry the refuse, having yet some grain, back to the hopper to be again carried through the machine.

In the accompanying drawings, which form a part of this specification, Figure 1 is a side 40 elevation of the machine, the casing-wall being broken away to show the relations of the screens. Fig. 2 is a longitudinal section; Fig. 3, an enlarged detail of the upper or primary screen, and Fig. 4, a detail in section.

45 To enable others skilled in the art to which the invention relates to make and use the invention, I will describe the construction and mode of operation of the same, referring by letters for this purpose to the accompanying drawings.

50 A designates the main casing, having the

ordinary bearings for a fan-shaft and fan B at the front, and a trough, C, is arranged transversely along the rear, in which trough revolves a worm-conveyer, C', designed to carry 55 the heavier refuse back to the hopper A' by means of an ordinary elevator. The hopper A' extends the entire width of the machine, to distribute the grain evenly over the screens, and the upper screen, D, is suspended at the 60 rear from the inner sides of the casing by hangers d.

Near the front end of the upper screen is journaled at d' a crank-shaft, d'', which has journals in opposite sides of the box and carries 65 a pulley, d', which by a belt connects it with the fan-shaft.

Pivoted about centrally, as at f, to the opposite inner sides of the casing A are two levers, F, and from pins f', near the upper ends 70 of these levers, are suspended by brackets g the rear end of the screen G, the forward end of said screen G being journaled at g' upon a crank-shaft, H, which in turn is journaled in the frame and connected to the power by a 75 pulley, h.

The lower screen, I, inclines in the direction of the fan or forwardly, and receives its motion by reason of being secured by brackets i to pins f'', near the opposite ends of the levers F.

The pivots of the levers F are about the middle of their length, as at f, and have their bearing in the side walls of the case. The rear ends of the screens I and G are respectively suspended from the opposite ends of the said levers F by means of the brackets i and g and the pivot-pins f' f''. Thus it will be seen that when motion is imparted to the crank-shaft H by means of belt from the 80 fan-shaft, the screen G will be vibrated, and will communicate motion to the screen I through the medium of its connections therewith. It will be observed that the first movement of the screen G will be rearward, carrying the upper ends of the levers F in a similar direction. This will move the lower ends of the said levers in the opposite direction, which will consequently move the lower screen, I, simultaneously and in an opposite direction 85 from the upper screen, G. The screen D not being directly connected with either the screen 90

95

100

G or I, it will be seen that its movement may differ in point of time or stroke from either of the latter-named screens.

The screens are made to fit snugly within 5 the walls of the casing, and the screens G, I, and D have each shedding-cleats *m*, as shown, to prevent grain from falling between the screens and the casing.

The screen G occupies an approximately-
10 horizontal position, and has an oscillatory movement, which delays the grain and so agitates it that without other provisions it would be liable to get between the said screen and the casing. To prevent this I provide flexi-
15 ble cleats *R*, which, secured at their upper edges to the inner surface of the case, fall over the edges of the cleats *m* upon either side of the screen.

The screen D has wires which run longitudinally of the same, and are secured in the end rails thereof. The side rails have inclined slots *s*, in which are received the ends of cross-pieces *S*, of sheet metal. Each of these cross-pieces *S* is composed of a leaf, *s'*, which, when 20 the parts are in place, presents an inclined side to the front of the machine, and an abrupt leaf, *s''*, which latter is arranged at an angle of about forty-five degrees with the leaf *s'*, and when the parts are in position these leaves *s''* 25 stand vertically in the screen. The leaves *s''* have their lower edges scalloped, as seen at *s''*, to form a number of faces, which will interrupt or distribute the blast and the flow of grain. The leaves *s'* *s''* are made of single 30 pieces of sheet metal, and the longitudinal wires *s* pass through perforations in both leaves.

The abrupt sides in the rapid oscillations or vibrations of the screen D serve to throw the chaff, &c., to the rear, while the heavier grain 40 rides down the inclines to the screen below, coming in contact with the faces *s''* or passing directly to the screen G. These faces *s''* equalize or distribute the blast around the screen D.

Modifications in details of construction may 45 be made without departing from the principle or sacrificing the advantages of the invention, the essential features of which will be readily understood from the foregoing description, taken in connection with the drawings. 50

Having thus fully described the invention, what I claim, and desire to secure by Letters Patent of the United States, is—

1. In a grain-separator, the combination, 55 with the casing and the vibratory screen D, of the screens G and I, the crank-shaft H, the levers F, having central pivotal bearings in the side walls of the casing, and the devices connecting them with the screen, substantially as specified.

2. The screen D, composed of the side rails having slots, the end rails, the longitudinal wires, and the bent cross-bars of sheet metal arranged in said slots and upon said wires, 60 and having inclined leaves on their front faces, and scalloped abrupt leaves *s''* on their rear faces, as and for the purposes set forth.

In testimony whereof I affix my signature in presence of two witnesses.

ISRAEL HESS.
